UNITED STATES PATENT OFFICE.

CHARLES LEWIS GEROLD, OF MILWAUKEE, WISCONSIN.

PRICE TABLET AND THE LIKE.

Application filed November 6, 1925. Serial No. 67,252.

To all whom it may concern:

Be it known that I, CHARLES LEWIS GEROLD, a citizen of the United States, and resident of Milwaukee, in the county of Milwaukee and State of Wisconsin, have invented certain new and useful Improvements in Price Tablets and the like; and I do hereby declare that the following is a full, clear, and exact description thereof.

10 This invention relates to a price tablet or marker.

Objects of this invention are to provide a novel form of price tablet or marker which is adapted to be used in either of two ways, 15 in one of which it may be stuck in the material and project upwardly therefrom, and in the other mode of use it is adapted to cooperate with a similar marker and stand upon a counter in a stable manner.

20 Further objects are to provide a plurality of independent and distinct markers of identically the same construction, so that any marker may be used as a backing for some other marker to display the desired 25 price or other matter.

An embodiment of the invention is shown in the accompanying drawings, in which:—

Figure 1 is a view of a marker.

Figure 2 is a side elevation partly in section showing the marker backed or propped up by a second marker.

Figure 3 is a perspective view of a pair of tablets assembled employing one of the same as a support.

35 Throughout the description and claims, the term "marker" will be employed to avoid needless repetition. It is to be understood, however, that this term is used in its generic sense and is not to be understood 40 as of a limited nature.

Referring to the drawings, it will be seen that the marker comprises an enlarged body portion 1 upon which the price may be indicated, as for instance, by means of numbers printed thereon in contrasting colors, 45 as indicated at 2. This body portion may be made of any desired shape, preferably of two oval half sections which have downwardly curved portions 3. This body por-

tion is provided with a pair of downwardly projecting feet or prongs 4 on its lower side. On the upper side the marker is provided with a transverse slot 5 which opens outwardly through a constricted passageway 6. The length of the slot 5 and its width is 55 such as to accommodate the prongs 4 of a second marker. The marker may be formed of any suitable material such as celluloid, bakelite, metal or in fact any material having the desired characteristics. 60

In using this marker, it may be employed singly, if desired, with the prongs stuck into a suitable support, for example, they may be stuck into the material if desired. When, however, it is desired to place the 65 marker upon a flat surface without sticking the prongs into the material, the method shown in Figure 2 is employed. In this case, the prongs 4 of the marker 1 are passed through the slot 5' of a second 70 marker 1'. The prongs or feet 4 rest upon the support 7 and the prongs or feet 4' of the marker 1' also rest upon the support. The interlocking of these markers insures a 75 secure bracing or backing for the displayed marker 1 and the spaced feet of the two markers prevent lateral tipping of the device.

It will be seen that a very simple and inexpensive marker has been provided 80 which may be used in either of two ways, as described in detail above, and it is to be noted that all of the markers are of identical construction except, of course, for varying 85 prices marked thereon.

Although the invention has been described in considerable detail, it is to be understood that the invention may be variously embodied and is, therefore, to be limited only 90 as claimed.

I claim:

1. The combination of a pair of markers each having a body portion provided with a slot adjacent its upper edge and with a pair of prongs extending from its lower edge, 95 one of said markers having its prongs passed through the slot of the other marker, whereby the prongs of each marker are

adapted to rest upon a support to thereby display one of said markers.

5 2. A marker comprising an enlarged body portion adapted to receive insignia and having a transverse slot adjacent to its upper portion and a pair of depending prongs adjacent to its lower portion, the slot being provided for the reception of a pair of

prongs of a like marker unit whereby the said last named marker unit serves as a base 10 support for the companion marker.

In testimony that I claim the foregoing I have hereunto set my hand at Milwaukee, in the county of Milwaukee and State of Wisconsin.

CHARLES LEWIS GEROLD.
